Inventor,
H. W. Steege, by
G. C. Kennedy,
Attorney.

UNITED STATES PATENT OFFICE.

HENRY W. STEEGE, OF WATERLOO, IOWA.

STANCHION.

Application filed December 29, 1924. Serial No. 758,766.

To all whom it may concern:

Be it known that I, HENRY W. STEEGE, citizen of the United States, residing at Waterloo, in the county of Black Hawk and State of Iowa, have invented certain new and useful Improvements in Stanchions, of which the following is a specification.

My invention relates to improvements in stanchions, such as are used as parts of the cattle furniture in stables, and the object of my improvement is to provide improved operating means for stanchions, such as will be easily operated from front or rear and be self-locking in either closed or open positions, and as a further object to suspend the stanchions in such a manner as to keep them always in a medial position relative to side supports or standards and prevent them from assuming positions angular to a plane passing vertically through said supports.

These objects I have accomplished by the means which are hereinafter described and claimed, and which are illustrated in the accompanying drawings, it being understood that minor changes or variations in any of the parts or their arrangements will nevertheless be covered by my invention.

In said drawings Figs. 1 and 2 are respectively rear elevations of my improved stanchions in a closed and an open position. Figs. 3 and 4 are respectively front elevations of said stanchions in a closed and in an open position, the upper parts only being shown, other parts and the supporting means being removed or broken away. Fig. 5 is a top plan of the top operating means of the stanchions.

The numeral 12 denotes a horizontal pipe mounted in couplings 13 on the tops of spaced tubular standards 14 whose lower ends are embedded in or otherwise fixed in a floor or base 6. A pair of spaced couplings or sleeves 11 are mounted medially on the pipe 12 and have apertured lugs to which are connected short chains 10 whose lower ends are brought together obliquely and connected to a ringed hook 9 which in turn has its depending hook inserted in a medial hole 8 in a small hollow housing 7.

The numerals 1 and 2 denote a pair of stanchions whose lower ends are recurved toward each other and hinged together on a pintle 3 to which is connected one end of a short chain 4 whose lower end is connected

to a ring-bolt 5 embedded in the floor 6. 55 The upper ends of the stanchions are recurved toward each other and flattened plugs 15 are mounted and secured in their ends to project thereabove inclinedly. On these parts 15 are fixed as by welding or otherwise like flattened arms 17 and 18 respectively to be apposed in parallel and in contact to slide back and forth upon each other, the arms being curved on an arc whose radius centers in the pintle 3. The housing 65 7 is open at opposite ends in the plane which passes vertically through the standards 14, and the said arms 17 and 18 are passed through this housing.

Referring first to the rear elevations shown 70 in said Figs. 1 and 2, the numeral 23 denotes a short rock-shaft mounted in a pair of aligned bearing apertures in opposite front and rear walls of the housing 7 to project oppositely therefrom. On these oppositely 75 projecting ends of the rock-shaft are fixed short cranks 22 and 29 respectively of the same lengths. A link 20 is pivotally connected at its ends at 19 and 21 respectively to the member 15 on the stanchion 1 and to the said crank 22, and a stop pin on the housing 80 limits downward movement of the crank 22.

Referring to said Figs. 3 to 5 inclusive, a like link 30 has its opposite ends pivoted respectively to the member 15 on the stanchion 2 and the crank 29 by means of pintles 26 and 31. A coiled spring 27 is mounted on the pintle 26 with one end engaged with a headed pin 28 fixed in the said member 15 85 and its other end secured in a hole in the link 30.

The numeral 25 denotes a flanged plate secured on the front of the housing 7 to project therefrom at one end over the member 95 15 on the stanchion 1. The horizontal flange of this plate serves as a guard over the crank 29 to prevent accidental impacts, as from a cow's horn, from rocking down the crank to thereby cause the opening apart of the 100 stanchions. A pin 24 fixed in this plate serves as a stop for this crank in moving upwardly at the left.

In the opened position of the stanchions 1 and 2 shown in Figs. 2, 4 and 5, the arcuate 105 arms 17 and 18 have been moved slidably outwardly but not far enough to remove their extremities from the housing 7. The

stanchions may be thus spread apart by the operator when in front of the stanchions by pushing downwardly the connected crank 29 and link 30 past a dead center whereupon 5 the relatively heavy stanchions 1 and 2 in having thus been caused to pass outwardly beyond their centers of gravity will swing outwardly farther to the limits imposed by the connections of the links 20 and 30 to the 10 plug-members 15. In their opened positions, however, the crank and link connections cannot pass beyond a dead center because of the stopping of the crank 29 at the stop-pin 24 and the stopping of the crank 15 22 by the stop-pin 32. The stanchions are 20 yieldingly held apart by the spring 27. In case the operator is standing in the rear of the stanchions, he may open the stanchions by manually swinging upwardly the connected crank 22 and link 20 past a dead center so that the stanchions in likewise 25 spreading apart beyond their centers of gravity will then swing outwardly to their limits of movements.

25 The stanchions are closed together by merely swinging them towards each other, in so doing rocking the rock-shaft 23 reversely by means of the connected links and cranks already described, and the spring 27 30 yieldingly holding the parts in their closed positions but not passed beyond a dead center on either side, so that they may be reopened in the way already described. These 35 operating parts in both opened and closed positions are so held or interlocked that the animal cannot release them to cause an opening of the stanchions.

Particular attention is invited to the manner of supporting or suspending the stanchions from the pipe support 12 to cause the 40 stanchions to swing back into a normal position in the vertical plane of the support when displaced or rocked horizontally. This is effected by hanging the housing 7 45 medially on the downwardly converging chains 10 which hang in said vertical plane, and which tend to yieldingly resist rocking displacements of the stanchions from said plane. The chains also suspend the stanchions medially between the standards 14, and 50 thus keep the stanchions in a proper positional relation to the animal inclosed thereby for comfort and security, as well as for operation in opening and in closing.

55 Having described my invention, what I

claim as new, and desire to secure by Letters Patent, is:

1. In combination, an elevated support, an open-ended housing suspended from said support, a pair of stanchions swingingly connected at their lower extremities and having at their upper ends arcuate arms in parallel relation mounted within said housing to slide past each other, and resiliently controlled operating connections movably connected to and between said housing and the upper parts of the stanchions, operable to be moved past their dead centers and swing the stanchions to and fro to closed and opened positions and to yieldingly resiliently lock them in both of said positions. 70

2. In combination, an elevated support, an open-ended housing suspended swingingly from said support, a pair of stanchions hinged together at their lower ends and having their upper parts recurved to slide past each other and through said housing, a rock-shaft mounted in said housing, cranks on opposite ends of the rock-shaft, links connected between said cranks and the adjacent stanchions, a guard flange mounted fixedly on said housing above one connected crank and link to prevent accidental rocking of the crank, and a resilient connection between one stanchion and one of said links adapted to yieldingly retain the stanchions at open and closed limits of their movements. 75

3. In combination, an elevated support, an open-ended housing flexibly suspended therefrom to be retained yieldingly in a certain vertical plane, a pair of stanchions below said housing, hinged together at their lower extremities and having their upper parts bent inwardly slidingly past each other in an arc of a radius from said hinged connection, said arcuate parts traversing said housing, a rock-shaft mounted in said housing having cranks on its opposite ends, links pivotally connected between said cranks and the adjacent stanchions, means for preventing the passage of the connected cranks and links past their dead centers in certain directions, and a resilient connection between one of said stanchions and one of said links tending to yieldingly and resiliently retain the stanchions in either their open or closed positions. 90

In testimony whereof I affix my signature.

HENRY W. STEEGE.
